Fig. 4

Fig. 1 is a perspective view of a language listening booth showing our new design;

Fig. 2 is a vertical sectional view thereof on the plane of line 2—2 of Fig. 1 looking in the direction of the arrows;

Fig. 3 is a front elevational view thereof; and

Fig. 4 is a top plan view of the same.

The language listening booth is conventionally plain when viewed from the rear.

The characteristic features of our design reside in those portions shown in full lines on the drawing.

We claim:

The ornamental design for a language listening booth, as shown and described.
